UNITED STATES PATENT OFFICE.

CICERO HINE, OF CHICAGO, ILLINOIS, ASSIGNOR TO THE BRUNSWICK BALKE COL-
LENDER CO., OF CHICAGO, ILLINOIS, A CORPORATION OF DELAWARE.

DESIGN FOR A GAME-TABLE.

42,465.

Specification for Design.

Patented May 7, 1912.

Application filed January 6, 1912. Serial No. 669,873. Term of patent 14 years.

To all whom it may concern:

Be it known that I, CICERO HINE, a citizen of the United States, residing at Chicago, in the county of Cook and State of Illinois, have invented a new, original, and ornamental Design for Game-Tables, of which the following is a specification, reference being had to the accompanying drawing, forming a part thereof and showing a

perspective view of a table embodying my invention.

I claim:

The ornamental design for a game table as shown.

CICERO HINE.
